US0D1047981S

(12) **United States Design Patent** (10) **Patent No.:** **US D1,047,981 S**
(45) **Date of Patent:** **** Oct. 22, 2024**

(54) **EARPHONE**

(71) Applicant: **Guangzhou Atlantis Technology Co., Ltd.**, Guangzhou (CN)

(72) Inventor: **Enhao Zhang**, Guangzhou (CN)

(73) Assignee: **Guangzhou Atlantis Technology Co., Ltd.**, Guangzhou (CN)

(**) Term: **15 Years**

(21) Appl. No.: **29/936,208**

(22) Filed: **Apr. 8, 2024**

(51) LOC (14) Cl. **14-01**

(52) U.S. Cl.

USPC **D14/223**

(58) **Field of Classification Search**

USPC D14/205, 206, 207, 217, 221, 223, 225;

(57) **CLAIM**

The ornamental design for an earphone as shown and described.

DESCRIPTION

FIG. 1 is a top perspective view of an earphone, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is its split state diagram.

The broken lines in the drawings illustrate the portions of the earphone, which form no part of the claimed design.

1 Claim, 9 Drawing Sheets
